CRYSTAL AMPLIFIER DEVICE

Salvatore F. Amico, East Boston, Mass., assignor
to Sylvania Electric Products Inc., Salem, Mass.,
a corporation of Massachusetts

Application July 24, 1948, Serial No. 40,562

6 Claims. (Cl. 175—366)

1

This invention relates to semi-conductors such as crystals and particularly to such devices useful as amplifiers, oscillators and the like.

An object of the invention is to provide an effective crystal unit having at least three contacts, one of which may act as a control electrode to enable the device to act as an amplifier or the like.

A feature of the invention is a pair of flat metal strips in transverse contact with the apex line of a wedge-like crystal.

Other objects, features and advantages of the invention will be apparent from the following specification and its accompanying drawings, in which:

Figure 1 is a longitudinal section through the axis of a device according to the invention, and Figure 2 is another longitudinal section of the same device, taken through the longitudinal axis in a plane perpendicular to that of Figure 1. In the figures two thin sheets of strips 1, 2 of metal may be held together by cement, for example a plastic cement, so that the two metal strips 1, 2 are insulated from this assembly by the insulating layer 3. This assembly 1, 2, 3 is then cemented into the center of a plastic bead or cylinder 4, or the bead or cylinder 4 can be molded around the laminated structure 1, 2, 3. If desired the laminated metal strips 1, 2 may be bent into S-shaped form for proper resilience either before or after being cemented together as described. The spacing between the metal strips 1, 2 may be varied from an extremely small value up to 0.002 inch, and the dimensions of each metal strip 1, 2 may be varied, for example, in width and thickness to give the proper spring stiffness. For example, the insulating layer 3 may be 0.001 inch and the metal strips 1, 2 may be 0.003 inch thick, 0.006 inch width and $\frac{3}{4}$ inch long, and may be for example of tungsten or another similar metal. An alloy of platinum with 13 per cent rhodium works very well.

The ends of the metal strips 5, 6 in contact with the crystal may be machined to a sharp edge as shown, somewhat like a chiselled edge, but of course much sharper or in some cases the edge may be applied by well known electrolytic means. The actual edges 7, 8 may be on the nearer side of the two metal strips as shown in order to have them as close together as possible. The insulating layer 3 ends a short distance before the edge. The included angle of each point may be for example 45°. The edges 7, 8 and should be within 0.001 inch of each other measured along the longitudinal axis of

2

the metal strips in other words the two edges should be substantially in a plane perpendicular to the axis of the metal strips.

The plastic bead 4 is inserted into a metal cartridge 9 having a slightly smaller inside diameter than the outside diameters of the bead 4, the difference, for example being 0.001 inch. The bead is preferably inserted so that its top or outside surface 11 is about $\frac{1}{8}$ of an inch from the end 12 of cartridge 9. A metal plug 13 carrying a piece of semi-conductor crystal 16 soldered thereto is inserted into the metal cartridge 9 from its other end 14. The metal plug 13 should have a slightly larger outside diameter, for example 0.001 inch larger diameter, than the inside diameter of the metal cartridge 9, in order that the plug 17 may be inserted into a cartridge 9 as a forced fit. The solder 15 attaches the semi-conductor crystal 16 to the metal plug 13 and to the wire pigtail connection 17.

The crystal 16 may for example be of germanium having incorporated therein a small amount of tin, for example 0.1%, as an actuating impurity often called a donator or acceptor impurity. The crystal is formed to have a sharp apex edge 18, the top 19 of the crystal being made wedge shape for that purpose with the sides 20 and 21 leaning on the apex line. The crystal 16 being placed so that said apex line 18 is substantially in the plane as the edges 7 and 8 of wire strips 1 and 2 and perpendicular to the longitudinal axes of said wires. The edges 7, 8 are then perpendicular to the edge 18, and the contact on the germanium will therefore be a point contact. The included angle between the surfaces 21 and 20 of the germanium crystal 16 may be for example about 150°. The crystal is suitably polished and etched to give proper electrical characteristics, for example being polished with 4/0 emery paper and oil polish and chemically etched.

The plug 13 is advanced into the cartridge 9 until contact is just made, as may be indicated in an ohmmeter, and subjected to alternating current pulses to about 25 volts with a current limiting resistor for example of about 10 ohms in series. The pulses should be very short. After this pulsing, the plug 13 may be pushed very slightly forward so as to bend the spring to secure proper electrical characteristics in the forward current carrying direction. About five milliamperes at one volt direct current for each contact may be satisfactory, for example, although other pulsing may be used for other purposes.

Reference is hereby made to my copending application Serial No. 40,561, filed concurrently herewith and to application Serial No. 39,665, filed July 20, 1948, by Frederic Koury, these applications all being assigned to a common assignee. These applications all contain disclosure and claims for multiple sharp contacts engaging a semiconductor, the sharp contact elements being separated by insulation.

What I claim is:

1. A semiconductor unit comprising a wedge-shaped semiconductor crystal, and two metal strip contacts, an insulating layer cementing said strips together and spacing them from contact with each other, said strips engaging said body sufficiently close to each other to effect interaction and engaging the edge of the wedge-shaped crystal perpendicularly to give substantially point contacts.

2. The combination of claim 1, in which the insulating layer is of less than 0.002 inch thickness.

3. The combination of claim 2, in which the metal strips have sharp edges beveled toward the ends of the strip nearest each other.

4. A semi-conductor unit comprising a body of semi-conductive material having an edge, a contact of large area engaging said body, and two additional contacts having sharp edges mutually close to each other and transverse to the edge of the semi-conductive body and in engagement therewith.

5. A semiconductor unit including a body of semi-conductive material having an edge, a contact of large area engaging said body, and two additional contacts having sharp edges mutually close to each other and transverse to the edge of the semi-conductive body and in engagement therewith, the two additional contacts being spaced from each other and from the edge of the body.

6. A semi-conductor unit comprising a body of semi-conductive material having an edge, a contact of large area engaging said body, and two additional contacts having sharp edges mutually close to each other and transverse to the edge of the semi-conductive body and in engagement therewith, the two additional contacts being spaced from each other and from the edge of the body, the two additional contacts being spaced from each other and from the edge of the body.

7. A semi-conductor unit comprising a body of semi-conductive material having an edge, a contact of large area engaging said body, and two additional contacts having sharp edges mutually close to each other and transverse to the edge of the semi-conductive body and in engagement therewith, the two additional contacts being spaced from each other and from the edge of the body, the two additional contacts being spaced from each other and from the edge of the body.

semiconductive material having an edge, a contact of large area engaging said body, a pair of resiliently contoured strips cemented together and thrust endwise against said edge, said strips being formed each with a sharp edge, and the edges of said strips extending close to each other and transverse to the edge of said body.

6. A semi-conductor device comprising a block of semi-conducting material having an edge, two metallic electrode members extending substantially at right angles with and across said edge, each of said members consisting of a ribbon having a sharp portion contacting said edge to provide a small-area contact with said block, and a further electrode providing a low-resistance contact with said block.
